Rosewell Thompson Inventor;
Albert Gantlett, Walter E. Bennett,

UNITED STATES PATENT OFFICE.

WALTER E. BENNETT, OF BOSTON, MASSACHUSETTS, ASSIGNOR TO THE MORLEY BUTTON SEWING MACHINE COMPANY, OF SAME PLACE.

METHOD OF ATTACHING BUTTONS.

SPECIFICATION forming part of Letters Patent No. 367,334, dated July 26, 1887.

Application filed March 30, 1887. Serial No. 233,005. (No model.)

To all whom it may concern:

Be it known that I, WALTER E. BENNETT, of the city of Boston, in the county of Suffolk and State of Massachusetts, have invented a new and Improved Method of Attaching Shank-Buttons to Boots, Shoes, and other Fabrics; and I do hereby declare the following to be a full, clear, and exact description of the stitch which secures the button to the fabric and the manner of forming the same, reference being had to the accompanying drawings, making a part of this specification.

The object of my invention is to secure shank-buttons to boots, shoes, and other fabrics by means of a cord or thread in such a manner as to insure both strength and neatness, and I attain this result by manipulating the thread, as follows: first drawing a loop of thread through the fabric outside of the button-eye, then forcing said loop through the button-eye and fabric, then drawing another loop of thread through the first loop while under the fabric, then drawing the second loop of thread through the fabric outside the button-eye and throwing it over the body of the button, after which the slack thread under the fabric is pulled with sufficient force to draw the loops snugly through and about the fabric and button-eye, all of which will hereinafter be fully explained.

I will now describe the formation of my improved stitch with reference to the accompanying drawings.

Similar letters of reference indicate corresponding parts.

Figure 1 represents the first loop of thread drawn through the fabric outside the button-eye; Fig. 2, the same loop forced through the button-eye and fabric. Fig. 3 shows said loop thrown back a short distance. Fig. 4 represents another loop of thread drawn through the first bent loop. Fig. 5 shows the second loop drawn through the fabric outside the button-eye; Fig. 6, the same thrown over the body of the button. Fig. 7 is a side view of a completed stitch. Fig. 8 is a perspective view of a strip of fabric upon which a few buttons have been secured and then bent C-shaped, so as to clearly show the appearance of my improved stitch upon both sides of the material.

A represents the fabric upon which the button is secured. B is the button. C is the first or

primary loop of thread, and D is the secondary or locking loop.

In securing a button to the fabric I place it upon the material in an inclined position, so that both the body and shank may rest upon the goods, as shown in the drawings. I then pull a loop of thread, C, through the fabric a short distance outside the button-eye, as shown in Fig. 1. I then force said loop through the button-eye and fabric in the manner shown in Fig. 2. I then pull the loop back a short distance past the first hole made in the material, as shown in Fig. 3. I then pull another loop of thread, D, through loop C, as shown in Fig. 4, after which I pull loop D through the fabric outside the button-eye in about the same place loop C was drawn through, as shown in Fig. 5, after which I pass loop D over the body of the button, as shown in Fig. 6, the stitch being completed and the button neatly and strongly secured to the fabric by exerting sufficient force upon the thread which is under the material to draw the latter-mentioned loop snugly about the two threads which composed the first loop, as shown in Figs. 7 and 8, loop C having previously been drawn snugly about the base of loop D under the fabric by the action of drawing the latter through it and the material, as shown in Fig. 5. This stitch may be formed by hand or by suitably-organized mechanism.

Having thus fully described my improved method of attaching shank-buttons to boots, shoes, and other fabrics, I claim as new and desire to secure by Letters Patent—

The method of attaching shank-buttons to fabrics, the same consisting in first drawing a loop of thread through the material outside the button-eye, then forcing it through the button-eye and fabric, then bending it back while under the material and drawing another loop of thread through it, then drawing said second loop through the fabric outside the button-eye, then passing the second loop over the head of the button, and finally exerting sufficient strain upon the thread which is beneath the material to tighten said second loop about the threads which have been passed through the button-eye, as shown and described, for the object set forth.

Witnesses: WALTER E. BENNETT.

ROSEWELL THOMPSON,
ALBERT H. SAWTELL.
